FIG. 1

FIG. 2

Inventor
William Stuart Webster

By E. H. Webster Attorney

Patented Nov. 27, 1923.

1,475,667

UNITED STATES PATENT OFFICE.

WILLIAM STUART WEBSTER, OF BRIGHTON, MASSACHUSETTS.

RHEOSTAT.

Application filed November 20, 1920. Serial No. 425,371.

To all whom it may concern:

Be it known that I, WILLIAM STUART WEBSTER, a citizen of the United States, residing at Brighton, in the county of Suffolk and State of Massachusetts, have invented certain new and useful Improvements in Rheostats, of which the following is a specification.

My invention relates to rheostats and has 10 for an object thereof to provide a device of this character which will permit better ventilation than is possible with rheostats now known.

Another structural advantage of my invention resides in the dual function of the pins, the pins acting both as supports for the wire winding and as contacts.

With the above general objects in view and others which will be obvious to those skilled 20 in the art from the description hereinafter, my invention consists in the features, details of construction and combination of parts which will first be described in connection with the accompanying drawings and then 25 particularly defined in the claims.

In the drawings:

Figure 1 is a side elevation of the apparatus, parts being in section, and

Figure 2 is a plan view of the lower side 30 of the rheostat.

Two insulating discs 1, 2, are held in spaced relation by means of shoulders 3, 3, formed on the spindle bearing 4. Adjacent the periphery of each of these discs is a series of escutcheon pins 5, and the resistance wire 6 is progressively laced between the two discs, passing under the heads of the escutcheon pins. The pins also act as contact members.

40 The discs and the resistance wire winding carried thereby, may be secured to a micarta panel 7 by any desirable means such as by screws (not shown) passing through the upper disc and into the panel, spacing washers 8 surrounding the screws. If desired, spacing members 9 may also be inserted between the discs.

A spindle 10 passes through the spindle bearing 4 and panel 7, and secured thereto 50 at its upper end is a pointer 11 and an ordinary hard rubber operating knob 12.

Washers 13 are mounted on the lower portion of the spindle which may be reduced as shown, and between these washers the

contact brush 14 is positioned. A nut 15 secures these members in place.

55 The terminals of the rheostat are indicated by numerals 16 and 17, a flexible metallic conductor 19 connecting the latter terminal with the brush. Numeral 18 refers to blank contacts.

The operation of the device will be obvious. By rotating the operating knob 12 the brush 14 will be caused to travel over the contact pins and cut in the desired amount of resistance, the pointer 11 indicating the position of the brush.

A rheostat of the character described is very compact and permits splendid ventilation thereby preventing undue heating.

70 While I have shown and described only one contact brush and that located on the under side of the apparatus, it will be apparent, of course, that, with slight modifications in the mode of attaching the rheostat 75 to the panel, the brush could be positioned on the upper side of the rheostat, or if desirable, two brushes may be used, one on each side. By such an arrangement finer adjustments could be obtained as it would 80 be possible to secure contact at each half turn of wire.

Having fully described my invention what I claim as new and desire to secure by Letters Patent is:

85 1. A rheostat including spaced members, resistance wire laced between but outside the peripheries of said members, and means for holding said resistance wire in place.

2. A device of the character described 90 including spaced discs, resistance wire laced between said discs, and conductive means fixed to said discs over which said wire is uninterruptedly laced.

3. A device of the character described including spaced discs, resistance wire laced between but outside the peripheries of said discs, and a rotatable brush for variably utilizing the resistance of said wire.

95 4. A rheostat including spaced members having contact pins arranged adjacent the peripheries of said spaced members, resistance wire laced between the spaced members and around the pins, and a movable brush for making a variable connection with the 100 pins.

5. A device of the character described including spaced discs, contact pins arranged

adjacent the peripheries of said discs, resistance wire laced between the discs and around the pins, the pins acting both as an electrical connection and as a support for the wire, and a rotatable brush for making a variable connection with the pins.

6. A rheostat including a spindle, means for rotating the spindle, a bearing for the spindle, said bearing provided with shoulders, discs carried by the bearing and spaced by said shoulders, contact pins arranged adjacent to the peripheries of the discs, resistance wire progressively laced between said discs and around the contact pins, a brush carried by the spindle for making a variable contact with the pins, and a flexible metallic conductor connecting the brush with one of the rheostat terminals.

7. A rheostat including spaced members, a continuous wire of uniform resistance laced between said members, and means for utilizing each turn of said lacing as a progressive step in the resistance characteristics of said rheostat.

8. A rheostat including spaced members, a continuous uniform resistance wire uniformly laced between said members, and means for utilizing each section of said lacing as a resistance element in a rheostat of uniformly progressive characteristics.

9. A rheostat comprising spaced rows of conductive elements and a length of resistance wire uninterruptedly laced between the elements of said rows and in electrical contact therewith.

10. A device of the character described comprising spaced rows of conductive elements and resistance wire stretchedly laced between the elements of said rows and in contact therewith.

11. A rheostat comprising spaced rows of elements supporting resistance wire uninterruptedly laced therebetween, a movable contactor to progressively make contact with any desired number of said elements cooperatively arranged to conduct electrical currents from said wire to said contactor.

W. STUART WEBSTER.
